ADJUSTABLE AND COLLAPSIBLE CRUTCH

Silvey A. Jacobucci, Upland, Calif., assignor of
one-third to Mary E. Jones, Ontario, Calif.

Application May 31, 1938, Serial No. 210,918

3 Claims. (Cl. 135—50)

This invention has for an object the provision of an improved crutch which may be easily and accurately adjusted to suit children or adults of large or small stature, and also readily collapsed into small compass for a convenient placement in position of rest or storage in theaters, automobiles and confined spaces, or for use as a cane or "walking stick".

Another object of this invention is to provide a crutch of the character described which may be quickly and easily extended from collapsed position into position for use without necessitating adjustment to suit the particular user.

Another object of this invention is to provide an adjustable and collapsible crutch having a latch or detent which will automatically lock the crutch parts in a predetermined position when such parts are relatively extended, it being possible to conveniently adjust and set certain elements whereby upon extension of the crutch parts to position of use, the hand grip will be disposed at different predetermined heights to best suit the particular user.

Yet another object is to provide a crutch of the character described which readily lends itself to a simple, inexpensive, light-weight, strong and durable all-metal construction.

A further object is to provide a simple and efficient means for lengthening or shortening the crutch and a likewise efficient means for adjusting the hand grip, both of said means being subject to ready operation by the user of the crutch without use of special tools or requiring mechanical skill.

I have shown in the accompanying drawing a preferred form of an adjustable and collapsible crutch, embodying my invention, subject however, to modification within the scope of the appended claims, without departing from the spirit of my invention.

Referring to the drawing:

Fig. 1 is a fragmentary side elevation of a crutch made in accordance with this invention and as when extended;

Fig. 2 is a side elevation of the crutch as when collapsed;

Fig. 3 is an enlarged fragmentary detail view of the length adjusting means, partly in vertical section and partly in elevation;

Fig. 4 is a sectional view taken on the plane of line 4—4 of Fig. 1;

Fig. 5 is a fragmentary edge view of the upper part of the crutch;

Fig. 6 is an enlarged sectional view taken on the plane of line 6—6 of Fig. 5; and

Fig. 7 is a sectional view taken on the plane of line 7—7 of Fig. 6.

One embodiment of the crutch of this invention generally comprises a frame-like upper section A, a staff-like lower section B slidably joined thereto, a cross head C fixed to said lower section and slidable on the upper section, automatic latching means D embodied in said upper section and said cross head, and a length adjusting means E provided in the lower portion of said lower section.

As here shown, the upper section A comprises a suitable arm pit rest 1 and a V-shaped cross member 2 joined by spaced tubular upright members 3. The members 3 are rotatably mounted on bosses 4 and 5 carried by said rest and said cross member and whereby to selectively present in opposed relation to one another, openings of the sets 6, 7 and 8. Set screws 9 and 10 provide for securing the members 3 to said bosses.

The lower section B includes a tubular staff 11 slidable in a sleeve portion 12 of the cross member 2 and secured to by means of a set screw 13 to a boss 14 on the cross head C.

The cross head C includes sleeves 15 slidable on the members 3 and joined at their upper and lower ends by a grip member 16 and a tubular latch carrying member 17, from which latter the boss 14 extends. Slidable in the tubular member 11 so as to be extended therefrom by a spring 18 into the opposed openings of the sets of openings 6, 7 and 8, are latch bolts 18'. Handles 19 carried by said bolts extend thru slots 20 in the member 17 so as to be operable below the latter for retracting said bolts 17. The handles are 30 screwed into the bolts and are therefore removable. In this connection it is noted that the lower ends of the sleeves 15 are cut away or bevelled as at 20', whereby to facilitate insertion and removal of the bolts 18' and spring 18 when 40 said sleeves are removed from the members 3.

By turning the members 3 to present the openings of any one of the several sets 6, 7 and 8 in opposed relation, it being noted that these sets are spaced circumferentially and also in different horizontal planes, provision is made for disposing the grip 16 in different positions to suit children or adults of different stature. When adjusted as desired the set screws 9 and 10 are set so as to hold the upper section assembled and the members 3 in the predetermined position.

When the crutch is collapsed, as shown in Fig. 2, it lies in small compass and may be conveniently placed or held in a position of rest in a theatre,

automobile or other confined space, or may be used in this form as a walking stick.

When it is desired to use the crutch in the usual manner, the operator grasps the cross head C in one hand and with the other hand merely pulls upwardly on the upper section. When the bolts 18' register with the openings of the sets 6, 7 and 8, which are disposed in position to receive said bolts, the spring 18 forces said bolts into said openings and thereby automatically locks the crutch sections in extended position best suited to the particular user. The frictional engagement of the bolts with the sides of the members 3 will prevent unintentional movement of the crutch sections out of collapsed position and thus the latch means is, in effect, operative when the crutch is collapsed, as well as when extended.

While the adjustment afforded by turning the members 3 with respect to the latch bolts provides for a slight variation in the overall length of the crutch, the means D embodied in the lower part of the staff 11 makes possible adjustments whereby the crutch is adaptable for use by children and adults of all sizes. As here provided this means includes an extensible staff section 21 of tubular form and telescoped by the staff 11. This extensible section is split longitudinally as at 22 from the upper end thereof, so as to provide expansible jaw portions 23 adapted to frictionally engage the staff 11 and thereby hold the extensible section in adjusted position, aided by the transverse notches 24. A nut 25 is mounted in the bore of the extensible section 21 so that wedge shaped portions 26 thereof will engage between 35 and force apart the jaw portions 23, when an adjusting screw 27 is appropriately turned. This screw extends thru the bore of the member 21 and its head 28 is engaged with a washer 29 at the lower end of said member while the threaded 40 end thereof is turned in said nut. A spring 30 engaged between the nut 25 and a shoulder 31 on the screw 27 operates to return the nut to normal position when the screw is turned to allow the jaw portions to return to normal position. A rubber 45 cap 32 is frictionally held on the lower end of the staff 11 or extension 21, as the case may be, and conceals the head of the screw.

I claim:

1. A collapsible crutch comprising an arm pit 50 rest, a cross member, spaced upright members se-

cured to and rigidly joining said rest and said cross member, a staff slidably supported by said cross member, a crosshead fixed to said staff, slidably mounted on said upright members and having a portion serving as a hand grip, means embodied in said crosshead and said upright members for releasably holding said upright members and said staff against relative sliding movement, said means including a tubular member carried by said crosshead below said grip portion, bolts slideable in and extensible from said tubular member, and a spring for extending said bolts, said upright members having openings adapted to receive said bolts.

2. A crutch comprising an arm pit rest, a cross member having a sleeve portion between its ends, upright members secured to and rigidly joining said rest and said cross member and being rotatable relative thereto, said upright members having openings at circumferentially and longitudinally spaced points thereof, adapted to be brought into opposed relation upon rotation of said upright members, means for holding said members against rotation, sleeves slideable on said upright members, a hand grip member secured to and extended between said sleeves, a tubular member secured to and extended between said sleeves at a point spaced below said grip member, latch bolts slidably supported in said tubular member, spring means operative to force said bolts into said openings, and a staff member slideable in said sleeve portion and fixed at its upper end to said tubular member.

3. A collapsible crutch comprising an upper section, a staff slidably joined to said upper section, a crosshead fixed to the upper end of said staff and slidably mounted on said upper section and including a hand grip portion and a latch carrying member spaced below said grip portion, said upper section including upright members 40 having openings therein and adapted to be rotated to selectively present said openings in latching position, and latch means on said latch carrying member including bolts and spring means for automatically extending said bolts into 45 said openings upon movement of said crosshead into predetermined positions, and means for retracting said bolts.
